J. R. BOLDT ET AL

AIR CLEANER

Filed Oct. 10, 1925

INVENTOR.
David C. Ferguson.
John R. Boldt.
BY *L. V. Cullen*
ATTORNEY

UNITED STATES PATENT OFFICE.

JOHN ROBERT BOLDT AND DAVID CHARLES FERGUSON, OF BLAIREVILLE, INDIANA.

AIR CLEANER.

Application filed October 10, 1925. Serial No. 61,832.

This invention relates to air cleaners for carburetors.

It is a well known fact that carburetors are provided with an air intake that is very large in comparison with the jet nozzle supplying the combustible hydro-carbon used as a fuel. By reason of this very large air intake and, especially in the case of motor vehicles traveling over dusty roads, a considerable quantity of dust and dirt is apt to be drawn into the carburetor with the air to form the mixture.

The principal object of the present device is to provide an air purifier which, without materially cutting down the air supply to the carburetor, will thoroughly cleanse the incoming air from such dust and other impurities.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a vertical median section through an air purifier constructed in accordance with this invention.

Figure 2 is a section on the line 2—2 thereof.

Figure 3 is an enlarged plan view of a certain air valve used herewith.

In the embodiment of the invention herein shown there is provided a device having an intake connection or end 10 which leads through a reversely curved passage 11 into a circular chamber 12, the curved passage 11 being arranged substantially tangential to the chamber. The lower part of this chamber is surrounded by a frusto-conical wall 13 while the upper part is surrounded by an interrupted circular wall 14. Depending from the top of the chamber 12 and concentric with the chamber is a tubular member 14 open at the bottom and at the top communicating with an outlet passage 15 having an open outlet end 16. This end 16 may be connected to the carburetor by any suitable means such as an air hose or it may be screwed directly on to the carburetor, the connecting means forming no part of the present invention and consequently not being here

shown, the lower part of the frusto-conical wall 13 terminates in a substantially cylindrical wall 17. On the lower edge of this cylindrical wall is fitted a packing 18 which receives the top of a dust receptacle 19 of ordinary cylindrical form. Passing centrally through the receptacle 19 and the main body and its tubular portion 14 is a bolt 20 which has on each end a screw threading portion 21 engaged by a wing nut 22 which thus locks the several parts together. On the bolt 20 at the lower cylindrical part of the main chamber is a hollow frusto-conical spreader 23 and also on this bolt is fixed, just at the lower end of the tubular portion 14, a cylindrical valve 24 having a series of openings 25 in its bottom provided with lips 26. This valve has a flange 27 which surrounds the tube 14 in slightly spaced relation thereto to make an easy fit, the spacing being shown somewhat exaggerated in the drawing but, in actual construction, the diameter of this valve is such as to permit it to pass through the space within the wall 17.

It will be seen that this bolt has a triple function; it holds the parts together, it is used to adjust the spreader, and it is used to adjust the valve.

In use the entering air follows a spiral path, as indicated by the arrows, around the body and then passes up through the openings 25 and the tube 24 and out through the outlet 16. Owing to the downward spiral motion of the air the dust and dirt drop down between the baffle 23 and the walls of the lower portion 17 and collect in the receptacle 19. Meanwhile the clean air flows into the carburetor.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

Having thus described the invention, what is claimed as new, is:

1. In a device of the kind described, a body portion having an inlet and an outlet, the inlet being arranged to direct incoming air tangentially of the body and downwardly

thereof, a depending tubular portion arranged in the body and open at the bottom, said tubular portion having communication with a passage leading to the outlet, and a collecting receptacle below the body, said receptacle being detachable from the body, a bolt passing centrally through the body, the tubular portion and receptacle and securing the receptacle removably on the body, each end of said bolt being threaded and said ends projecting respectively through the top of the body and the bottom of the receptacle, and independent nuts on the opposite ends of said bolt whereby the bolt may be shifted vertically and the elements carried by said bolt be adjusted, and a frusto-conical baffle carried by the bolt and having its lower edge spaced from the inner wall of the body.

20 2. In a device of the kind described, a body portion having an inlet and an outlet, the inlet being arranged to direct incoming air tangentially of the body and downwardly thereof, a depending tubular portion arranged in the body and open at the bottom,

said tubular portion having communication with a passage leading to the outlet, and a collecting receptacle below the body, said receptacle being detachable from the body, a bolt passing centrally through the body, the tubular portion and receptacle and securing the receptacle removably on the body, each end of said bolt being threaded and said ends projecting respectively through the top of the body and the bottom of the receptacle, and independent nuts on the opposite ends of said bolt whereby the bolt may be shifted vertically and the elements carried by said bolt be adjusted, and a frusto-conical baffle carried by the bolt and having its lower edge spaced from the inner wall of the body, and a ported valve provided with directing lips carried by the bolt immediately below the tubular portion and having a flange surrounding said tube portions.

In testimony whereof we affix our signatures.

JOHN R. BOLDT.
DAVID C. FERGUSON.

thereof, a depending tubular portion arranged in the body and open at the bottom, said tubular portion having communication with a passage leading to the outlet, and a 5 collecting receptacle below the body, said receptacle being detachable from the body, a bolt passing centrally through the body, the tubular portion and receptacle and securing the receptacle removably on the body, each end of said bolt being threaded and said ends 10 projecting respectively through the top of the body and the bottom of the receptacle, and independent nuts on the opposite ends of said bolt whereby the bolt may 15 be shifted vertically and the elements carried by said bolt be adjusted, and a frusto-conical baffle carried by the bolt and having its lower edge spaced from the inner wall of the body. 20 2. In a device of the kind described, a body portion having an inlet and an outlet, the inlet being arranged to direct incoming air tangentially of the body and downwardly thereof, a depending tubular portion arranged 25 in the body and open at the bottom, said tubular portion having communication with a passage leading to the outlet, and a collecting receptacle below the body, said receptacle being detachable from the body, a bolt passing centrally through the body, the tubular portion and receptacle and securing the receptacle removably on the body, each end of said bolt being threaded and said ends projecting respectively through the top of the body and the bottom of the receptacle, and independent nuts on the opposite ends of said bolt whereby the bolt may be shifted vertically and the elements carried by said bolt be adjusted, and a frusto-conical baffle carried by the bolt and having its lower edge spaced from the inner wall of the body, and independent nuts on the opposite ends of said bolt whereby the bolt may be shifted vertically and the elements carried by said bolt be adjusted, and a frusto-conical baffle carried by the bolt and having its lower edge spaced from the inner wall of the body, and a ported valve provided with directing lips carried by the bolt immediately below the tubular portion and having a flange surrounding said tube portions. 45

In testimony whereof we affix our signatures.

JOHN R. BOLDT.
DAVID C. FERGUSON.

Certificate of Correction.

It is hereby certified that in Letters Patent No. 1,603,020, granted October 12, 1926, upon the application of John Robert Boldt and David Charles Ferguson, for an improvement in "Air Cleaners," an error appears requiring correction as follows: In the grant and in the heading to the printed specification the residence of the patentees is erroneously given as "Blairsville, Indiana," whereas said residence should have been given as *Blairsville, Pennsylvania*; and that the said Letters Patent should be read with this correction therein that the same may conform to the record of the case in the Patent Office.

Signed and sealed this 23d day of November, A. D. 1926.

[seal.]

M. J. MOORE,
Acting Commissioner of Patents.
